(57) CLAIM

We claim the ornamental design for a United States all military services flag, as shown and described.

DESCRIPTION

The sole FIGURE is a front view of the United States all military services flag of the present invention.

The broken line in the drawing represents a fold line. White background, all caps in bold black lettering. Top of flag and centered is the wording, "UNITED STATES OF AMERICA." Below the wording, centered is the seal of our Commander-in-Chief of the Military. Just below the seal of the Commander-in-Chief of the Military, is the Gadsden Flag (Don't Tread on Me). Arrayed from left to right just below the seal of the Commander-in-Chief of the Military and the Gadsden Flag, in a slight wide "V" shape are the seals of all branches of our services. Three words arranged in a slight curve shape from top to bottom on the left side of all seals, reads from bottom to top "PROTECT WE SHALL." Three words arranged in a slight curve shape from top to bottom on the right side of all seals, reads from top to bottom "DEFEND WE MUST." On the bottom left centered is the word "HOME," and on the bottom right centered is the word "ABROAD."
